UNITED STATES PATENT OFFICE.

BENJAMIN F. FORD, OF PORTLAND, MAINE.

WARP-TENSION-REGULATING DEVICE FOR LOOMS, &c.

SPECIFICATION forming part of Letters Patent No. 425,873, dated April 15, 1890.

Application filed October 26, 1889. Serial No. 328,314. (No model.)

To all whom it may concern:

Be it known that I, BENJAMIN F. FORD, a citizen of the United States, residing at Portland, in the county of Cumberland and State 5 of Maine, have invented certain new and useful Improvements in Warp-Tension-Regulating Devices for Looms, &c.; and I do hereby declare the following to be a full, clear, and exact description of the invention, such as 10 will enable others skilled in the art to which it appertains to make and use the same.

The invention relates to improvements in the tension mechanism of looms, the object being to keep the warp at a proper and steady 15 tension, so that it will not be drawn unevenly from the roller upon which it is wrapped nor slacken at any point between the said roller and the harness.

It is well known that the lay of a loom, when 20 driving home a woof-thread left by the shuttle in the shed of the warp, tends to produce slackness in the warp. This slackness it is 25 the intention of my invention to take up, and produce instead uniform tension at all times in the warp.

The invention consists in the construction and novel combination of parts hereinafter described, illustrated in the accompanying drawings; and pointed out in the appended 30 claims.

In the accompanying drawings, in which similar reference-letters designate corresponding parts, Figure 1 represents in vertical section parallel to the side a tension mechanism 35 such as described. Fig. 2 represents a side view of a modification in which the actuating-weight is outside of the warp. Fig. 3 represents an edge view of Fig. 2. Fig. 4 represents a section, parallel with the side, of a 40 modified form, in which the weights are deflected by fixed plates. Fig. 5 represents a side view of another modification, in which the warp may be tightened without changing the position of the weights. Fig. 6 is a view 45 of a modification having a hinged deflecting-plate. Fig. 7 represents one form of the invention in side view and shows the pawl which rides on the warp and the pawl which prevents the weighted wheel from falling too 50 far.

Referring to the drawings by letter, as shown

in Fig. 1, A designates a wheel mounted on the shaft *a* and having the warp *B* passed around or wound upon it. The sides of the wheel *A* are closed in, as shown in Fig. 2, and standing inward from its periphery are the similar non-radial partitions *C*, as shown in Fig. 1, which incline inward from said periphery and in the direction in which the warp moves when the loom is in operation. The said partitions are preferably equidistant and form with the sides of the wheel *A* the compartments or buckets *c c*. The periphery of the wheel *A* is closed and preferably has flanges 60 on its edges to prevent the warp from slipping from it.

D is a deflector or a cylindrical drum mounted on the shaft *a* within the wheel *A*, with its surface *d* sufficiently close to the inner edges of the partitions *C*, and *E* is a proper 70 weighting material—such as sand or shot—introduced into the wheel *A* and buckets *c* through a suitable opening *a'*, as shown in Fig. 2, in the side of the said wheel, which can be properly closed by a cover *a''*. It is 75 obvious that as the wheel is turned by the advance of the warp the buckets *c* will rise on the side opposite that upon which the lay is situated and will carry up the weighting material with them. When the said material 80 has risen to a certain height, the inclination of the partitions permits it to fall out of the corresponding buckets *c* upon the drum *D*, which directs it or from which it rebounds into the buckets below and is again carried 85 up. Thus the corresponding side of the wheel *A* is constantly weighted, and consequently 90 will pull back upon the warp and keep the latter under constant tension, the amount of which can be regulated by increasing or diminishing the amount of weighting material. Thus the tension can be increased or diminished as found necessary.

F designates a drum mounted on a shaft *f*, and around which the warp is passed from 95 the wheel *A* to prevent jar, because this drum, being placed between the loom and the wheel *A*, will prevent any irregular pulling on the warp.

In the above tension mechanism the warp 100 is outside the weight in the wheel *A*. To place the weight outside of the warp and thus

increase the leverage, and consequently the power, the warp is removed from the rim or periphery of the wheel A and placed on that of a wheel or drum G, mounted on the shaft 5 a adjoining the wheel A, as seen in Figs. 2 and 3, the diameter of the wheel G being less than that of the wheel A.

In the modification shown in Fig. 4 the drum D is replaced by a segment D', having 10 on the outer surface thereof the plates H, arranged in the arc of a circle concentric with the wheel A, said segment being supported upon the shaft a, the said shaft not rotating. Some of these plates may be hinged at their 15 inner edges, as shown in Fig. 6, so that the inner edges of the partitions C will strike them and turn their outer edges upward, forming with said partitions pockets to lift some of the weighting material and prevent 20 the fall thereof too soon. When the partitions pass, they will release the plates, and the latter will fall, causing the weighting material supported by them to discharge into the buckets below. In Fig. 6 the hinged plate is 25 held in the desired position by stop and spring h' h'', respectively. The stop h'', Fig. 6, prevents the hinged plate H from being turned up too far, and the spring h' will return the said plate to its normal position after being 30 depressed by the material. In practice one hinged plate H is sufficient, though two of such plates may be used, if desired.

Fig. 5 shows a modification in which a wheel I, of larger diameter than the weighted wheel 35 A, carries the warp. The wheel I has on its side a pivoted pawl J, which engages the teeth K around the rim of the wheel A. By this means the wheel I can be directly turned and the slack of the warp taken up without dis- 40 turbing or changing the positions of the weights.

In Fig. 7 is shown a circular ratchet k on one side of the wheel, over which the warp passes, and a similar ratchet L, but facing in 45 the opposite direction, on the opposite side of the weighted wheel. The ratchet k is engaged by a pawl k', which is pivoted upon the frame of the machine and the point of which rides on the warp, so that when the warp slackens

the pawl drops into engagement with the 50 ratchet k, and thereby the wheel A is prevented from turning, so that the warp cannot feed too fast from the said wheel. The ratchet L is engaged by a pawl l, and thereby the weighted wheel is prevented from falling too 55 far when the warp is slackened.

Having described my invention, I claim—

1. In a loom, the combination, with a large wheel provided with buckets around its periphery on the inside, having their inner ends 60 only open, of a deflector standing within said wheel, and the weighting material within the wheel and buckets and guided by the deflector, substantially as specified.

2. In a loom, the combination, with the 65 large wheel having buckets arranged around its periphery on the inside, which buckets have their inner ends only open and incline upward on the side farthest from the lay, of the drum mounted inside the wheel concentrically within the buckets, and the weighting 70 material, substantially as specified.

3. In a loom, the combination, with the wheel A, having the inclined buckets c, the drum within said wheel, and the weighting 75 material in the buckets, of the drum receiving the warp from the wheel A between the latter and the loom, substantially as specified.

4. In combination with the wheel having the series of interior peripheral buckets 80 adapted to hold the weighting material and provided with ratchet k on one side and ratchet L on the other, but facing in the opposite direction, and the pawls k' and l, whereby by the motion of the wheel is controlled. 85

5. The combination of a wheel provided interiorly at or near its periphery with a series of buckets opening inwardly, as described, and adapted for the reception of weighting material, with a deflector arranged within the 90 circle described by the buckets, as and for the purposes set forth.

In testimony whereof I affix my signature in presence of two witnesses.

BENJAMIN F. FORD.
